DEVICE FOR REMOVING ELEMENTS FROM
SHAFTS

Arthur Reeves, Halet, Quebec, Canada

Application May 25, 1942, Serial No. 444,297

1 Claim. (Cl. 29—284)

This invention relates to a device for removing elements from shafts and in particular the removal of detachable bits from the drill shaft or rod.

The invention will be illustrated with particular reference to the removal of detachable drill bits.

Detachable drill bits have been employed in mining operations, rock drilling and the like during recent years to an increasing extent and one difficulty particularly encountered has been the removal of the drill bits for resharpening or replacement. Normally, detachable drill bits are fitted very tightly on the drill shaft and during use sometimes become jammed on the shaft, even in those cases where an extremely tight fit is not made. To remove these bits make-shift methods are often employed which take up considerable time and which often necessitate that the shaft and attached bit be sent out to a machine shop for removal.

It is the object of the present invention to avoid the disadvantages of the prior art and to provide a simple and inexpensive apparatus through which elements including detachable drill bits may be removed from shafts.

A further object of the invention is to provide an apparatus of this kind which is compact and which may be transported very readily.

With these and other objects in view, the invention generally comprises a combination including a base, a superstructure rising above the base and means cooperating with the superstructure for clamping a shaft on the base with the detachable drill bit or element disposed clear of and spaced from the base and means for engaging the element, movable substantially in the axial direction of the shaft, for removing the element therefrom by percussion. Preferably the construction includes a pair of spaced apart side plates rising from the base with a wedge member designed to pass through the side plates to wedge the shaft in position.

The invention will clearly be understood by reference to the following detailed specification taken in conjunction with the accompanying drawing.

In the drawing:

Fig. 1 is a perspective view of the preferred form of device according to the present invention, showing a drill rod shank clamped in position and a removable tool positioned in contact with the detachable bit ready for removal.

Fig. 2 is a longitudinal section taken through Fig. 1.

Fig. 3 is a transverse section taken through the device adjacent to the point where the wedge passes through the structure.

Figs. 4 and 5 are transverse sections similar to Fig. 3 but illustrating the use of a shim in conjunction with the drill rod or shaft, the cross section of which in Fig. 5 is different from Fig. 4.

Figs. 6 and 7 are perspective views of shims which might be employed and which are illustrated in Figs. 4 and 5.

Fig. 8 is a transverse section on the line 8—8 of Fig. 2; and

Fig. 9 is a perspective view of a convenient form of tool used in combination with the device.

15 Figs. 10 and 11 are different forms of prong engaging ends which may be used in a tool as disclosed in Fig. 9.

Referring to the drawing:

20 A indicates a device for removing elements from shafts. B indicates a shaft and C an element (a detachable drill bit) mounted on the shaft. The device A in the preferred form includes a base 10 which may be provided with a secondary base plate 11 having mounted thereon a shaft supporting base or block 12. The block 12 is of a thickness so that its upper surface is vertically spaced from the base 10 to a fairly substantial degree. On each side of the block 12 a pair of plates 13 and 14 are mounted from the base plate 11, the plates 13 and 14 preferably being of angle iron having the horizontal flanges 15 so that they may be supported from the base plate in a simple and substantial manner. The plates 13 and 14 are designed preferably to abut the sides of the block 12 and are therefore in spaced apart relation to form therebetween a channel 16.

25 The plates 13 and 14 are formed with registering orifices 17 and 18 designed to receive therethrough a wedge member 19, the size and disposition of the orifices 17 and 18 are such as to cooperate with the wedge 19 in a practical manner so that the wedge may be caused to exert a downward pressure when driven through the orifices. These orifices are spaced upwardly from the upper surface of the block 12 a predetermined distance so that a shaft, drill rod or shank B may be disposed to lie upon or against the exposed surface of the block 12 and upon driving the wedge 16 through the orifices 17 and 18, such

30 member B is firmly clamped on the block 12 in frictional engagement with the latter throughout its extent. In the case of a drill rod such as illustrated in Figs. 1 and 2, the rod is so clamped that the detachable drill bit C is spaced from the base, both vertically and horizontally so that such

detachable bit is freely disposed in relation to other parts of the device.

The channel 16 provides a guideway through which a suitable tool D may pass to engage the protruding parts of the element to be removed from the shaft and the channel is such as to permit movement of the tool substantially in the axial direction of the shaft rod or shank to cause the element carried thereon to move axially and out of engagement therewith.

One suitable type of tool D is illustrated which includes the spaced apart prongs 28 and 29 offset as at 22 from the plane of the shank 23, the latter having an enlarged end 24 which may be readily struck with a maul, sledge or the like. The device is such that the enlarged end 24 of the tool protrudes rearwardly from the channel 16 and permits the free action of a sledge, maul or the like for subjecting the end to percussive contact such that the element may be removed quickly by percussion.

The base 10 preferably extends, in advance of the block 12 and side plates 13 and 14, as at 25 and terminates in a stop plate or baffle 26 so that in the case of smaller articles, particularly the latter, they are caught by the stop plate 26 and base extension 25 when forcibly removed from the shaft B so that they are held near the device and therefore may be quickly retrieved. Thus, rods, shafts or the like may be clamped in the device and elements removed therefrom in relatively quick succession. If desired, more than one pair of orifices such as 17 and 18 may be employed and spaced apart along the length of the side plates so that small lengths of shafting, etc. may be handled.

The base preferably has a U-shaped extension 27 projecting from the end opposite to the stop plate 26 and preferably the wedge 19 and the tool D are connected with the device by means of flexible elements such as the chains 28 and 29. Thus, the device is made into one complete compact unit.

In the case of the removal of pulleys, wheels, etc., from axles or shafts, this device is readily employed but to avoid any possible damage to the axle I preferably employ as indicated at 30 and 31 (Figs. 4 and 5) a shim which will suit the cross section of the shaft involved and which will cooperate with the wedge 19 to clamp the shaft in the device without injuring the shaft in any way.

The operation of the device is, of course, very simple. In terms of the removal of a detachable drill bit the drill rod is disposed in the channel 16 to lie upon the exposed surface of the block 12. The wedge is then quickly inserted through the orifices 17 and 18 and driven therethrough so as to tightly clamp the rod upon the block 12. The rod, of course, is initially placed on the block 12 so that the detachable drill bit C will project in spaced relation from the end of the block 12 and, of course, in spaced relation to the base 10. By inserting the tool B in the channel 16 and engaging its forked ends with the shoulder of the detachable drill bit, the latter will be readily removed from the shaft upon subjecting the end of the tool D to percussion. The drill bit in flying off the rod B will hit the stop plate 26 and in the majority of cases will lie ready to hand to be picked up and disposed in a suitable box or the like.

The rod B is easily removed by striking the opposite end of the wedge whereupon a new rod may be quickly inserted in its place and the same procedure followed.

The apparatus may, of course, be disposed horizontally or can be disposed vertically and in the latter case, if desired, the stop plate 26 may be used as a supporting medium for the device which, as will readily be appreciated, constitutes a simple compact unit which may be constructed economically, is comparatively light in weight and may readily be transported if desired.

What I claim as my invention is:

A device for holding shafts or the like comprising a base, a pair of parallel plates rising from the base forming therebetween a passageway in which to receive a shaft or the like, a block connected with said base and rising between said parallel members to receive a substantial portion of said shaft in bearing engagement, said block being of a length less than the length of the base and being designed to space the shaft from engagement with the base, the latter extending beyond said parallel members and said block, a pressure applying member designed to engage said shaft above said block, clamping means projectable through said plates and engageable with said pressure applying member to forcibly clamp said shaft on said block in said passageway.

ARTHUR REEVES.
